OIL TANK CLEANING APPARATUS

Bengt Olsson, Brooklyn, N. Y.

Application February 11, 1936, Serial No. 63,300

4 Claims. (Cl. 141—1)

My invention relates to an improvement in tank cleaning methods and apparatuses, and it is especially adapted for the removal of the oily viscous film which stubbornly adheres to the inner surfaces of the intricate and inaccessible structures like the double bottoms of maritime vessels. These tanks commonly used as storage place for the heavy and viscous fuel oils used by oil burning vessels, and due to the location and the cramped quarters of such tanks a thorough cleaning thereof is an extremely costly and slow undertaking. When repairs involving hot work like riveting and welding have to be done inside a double bottom tank, a thorough cleaning and gas freeing of the tank is required so that the work may be undertaken in perfect safety and without any danger of explosion. Also when a double bottom tank is changed to carry fresh water instead of fuel oil, or when deep and cargo tanks are changed from fuel oil to gasoline, palm oil or other refined product every vestige of the viscous oil film which stubbornly clings to the metal surfaces in the tanks, has to be removed before the change can take place.

Now however I have discovered that such cleaning may be done in a more economical and efficient manner and also in a much shorter time, by means of creating a fume laden steam and air circulation throughout the entire tank to be cleaned, and I use for my purpose any suitable fume generating solvent like carbon tetrachloride, kerosene et cetera in connection with my preferred apparatus, which employs steam as the circulating carrier, which is repeatedly circulated around the different inner tank surfaces and structures inside the tank. In passing such surfaces the steam will continuously tend to condense together with the fume, whereupon the fume will combine with the oil film and form a light flowing liquid which readily falls to the bottom of the tank from which it is afterwards removed or pumped, and the tank is left in a "skin clean" condition and every remote nook and cranny has been reached and cleaned.

I claim as part of my invention not only the apparatus employed, but I also claim the different steps taken as a method and as a part of my invention.

In the drawing:—

Figure 1 shows my preferred apparatus located in the wake of the lightening holes of the frames in the double bottom of an oil burning vessel.

Figure 2 shows the details of construction of my preferred apparatus on an enlarged scale.

Figure 3 represents a cross section of one frame

space of the double bottom and shows the general construction thereof and also the location therein of my preferred apparatus.

In the drawing where like reference characters denote corresponding parts, 1 denotes the ship, the double bottom tank 2 of which is shown being cleaned by my fume circulating process.

The double bottom tank 2 is divided into a series of frame spaces by the frames 3, which usually are spaced from two to three feet apart, and each frame space is further divided into three pockets by the lateral bulkheads 4. The division plates which form the honey-combed double bottom structure are provided with the centrally located lightening holes 5 and also with limber holes 6 at the top corners as well as at the bottom ones.

In the wake of the center row of the aforesaid lightening holes and oppositely directed, two of my preferred fume circulating devices 7 are placed, all as shown on the drawing.

Each of these devices comprises a flexible hose 8, to the end of which the circulating fluid jet pump 9, preferably steam driven, is attached.

The circulating pump 9 comprises the steam jacket 10, which is provided with the steam inlet 11 and into the threaded ends of which the pipes 12 and 13 are screwed. The longer pipe 13 is at one end provided with the solvent inlet 18, and it is to be noted that the other end of this pipe is provided with a tapered end, registering closely with the adjacent tapered end of the pipe 12, so as to form a narrow annular opening, which constitutes the steam jet nozzle from the high pressure steam jacket.

The high pressure steam, which is preferred for the operation of the jet circulating pump is furnished through the steam line 14, which is provided with the control valve 15 in the conventional manner. The conduit 16, through which the fume forming solvent is pumped into the pipe 13, is adapted to be connected to a conveniently placed solvent container not shown on the drawing.

The temporary manhole covers 17, preferably a couple of bags of saw dust, are shown stuffed around the flexible hose conduits 14 and 16 in such a manner that the manholes 19 are substantially plugged up so as to prevent the steam from escaping from the double bottom tank into the hold of the vessel.

The operation is as follows:—

The manholes 19 having been properly plugged, the steam valves 15 are opened and the solvent admission started, whereupon the steam jet issuing from the annular opening of the steam

jacket induces a high velocity air stream through the hose lines 8, and the fume forming solvent 28 is blown into a spray as shown diagrammatically in the Figure 2 of the drawing. The spray 28 in 5 entering and passing through the high pressure steam jet 21 is still further atomized and a fume laden steam cloud issues from each of the circulating pumps 9. These clouds are moving rapidly against each other, and in meeting the 10 clouds naturally will broom out laterally and fill the several frame spaces, and the powerful air suction at the outer ends of the double bottom tank will induce a circulating flow towards the ends of the tank. The resulting circulation is diagrammatically illustrated by the dotted lines 22 15 in Figure 1 of the drawing.

In passing through the several openings of the frame plates and in moving against said plates the steam clouds will still further broom out laterally and be distributed effectively over all the 20 inner surfaces of the tank structure, and the steam in contacting the surfaces will tend to condense thereon and the fume laden condensate deposited on the surfaces will effectively dissolve the 25 viscous oil film which adheres to the metal surfaces and drip to the bottom of the tank.

The fume circulation should preferably be maintained for a period of from one to two hours 30 depending upon the condition of the tank. After a sufficient circulation has been maintained in the tank, the steam and solvent supplies are cut off and the manhole covers are removed, and the material precipitated to the tank bottom is preferably removed by a process and device similar to 35 those shown in my pending application, Serial Number 30,434, by which the resulting sludge is removed by the ship pumps.

I am not limiting my claims for invention to the 40 apparatus shown, as it is obvious that modifications and alterations may be made in the adaptation of my device without departing from the scope and spirit of my invention.

I claim:—

1. The method of cleaning an oil storage tank, 45 characterized by placing an extended pipe line inside the tank to be cleaned, injecting a high pres-

sure steam jet into the pipe line so as to suck a high velocity air stream therethrough, injecting a solvent for oil into the air stream and causing said solvent to be suspended in the air stream when it enters the steam jet in a spray formation, further atomizing the spray by means of the steam jet force and causing the steam cloud issuing from the pipe line to broom out laterally and repeatedly circulating the fume laden steam cloud through the pipe line so as to substantially 10 reach all parts of the tank by said fume circulation. 5

2. The method of cleaning double bottom tanks on board maritime vessels, comprising the placing of a pair of oppositely directed extended pipe lines in the wake of a row of lightening holes in the tank to be cleaned, injecting a high pressure steam jet in the direction of the circulating flow 15 into each of the lines, injecting a solvent for oil so as to cause fume laden steam clouds to issue from said lines and to impinge one upon the other with sufficient velocity to cause a lateral brooming out 20 of the clouds and repeatedly circulating the resulting steam laden atmosphere through the extended pipe lines so as to substantially reach all 25 parts of the inner double bottom structure by said circulation. 35

3. An apparatus for cleaning of oil storage tanks comprising a circulating pipe line inside 30 said tank, a high pressure atomizing steam jet at the discharge end thereof, means for injecting an oil solvent into the line, a suction intake to the pipe line, said intake being remotely located in the tank from the discharge end of the circulating line. 35

4. A double bottom tank cleaning apparatus comprising in combination a pair of pipe lines oppositely directed toward each other substantially in the wake of a row of lightening holes, atomizing steam jets at the discharge ends of said lines, 40 means for admitting a solvent for oil into said lines and a suction intake to each of said lines located in the tank remotely from the discharge ends of said lines. 45

BENGT OLSSON.
